UNITED STATES PATENT OFFICE.

JOSEPH ONESIME DAUPHIN, OF RAT PORTAGE, CANADA.

ROD-SWAB.

SPECIFICATION forming part of Letters Patent No. 694,840, dated March 4, 1902.

Application filed June 11, 1900. Serial No. 19,898. (No model.)

To all whom it may concern:

Be it known that I, JOSEPH ONESIME DAUPHIN, a subject of the Queen of Great Britain, and a resident of Rat Portage, in the 5 Province of Ontario and Dominion of Canada, have invented a new and Improved Rod-Swab, of which the following is a full, clear, and exact description.

The purpose of this invention is to provide 10 a device for effectively wiping rods which move through stuffing-boxes—for example, piston or valve rods; and to this end the invention comprises a peculiarly-constructed case arranged to be attached to the stuffing-box bolts, so as to be held in immediate proximity to the stuffing-box.

This specification is the disclosure of one form of the invention, while the claim defines the actual scope thereof.

Reference is to be had to the accompanying drawings, forming a part of this specification, in which similar characters of reference indicate corresponding parts in all the views.

Figure 1 is a perspective view illustrating 25 the use of my invention. Fig. 2 is a sectional view thereof. Fig. 3 is a section on the line 3 3 of Fig. 2, and Fig. 4 is an edge elevation thereof looking from the right hand of Fig. 1.

In Fig. 1 the stuffing-box is represented by 30 the numeral 5, and 6 is the gland, which is held in place by the usual bolts 7. 8 indicates the rod which passes through the stuffing-box, as usual.

My improvement comprises a circular case 35 which is formed in two parts 9 and 10, the part 10 being the upper part and being hingedly connected with the lower part 9 at the point 11, the opposite end of the section 10 of the case being provided with a tongue 40 12, which fits into a corresponding recess in the adjacent end of the part 9. The sections 9 and 10 of the circular box are provided with

lugs 14, which are orificed to receive the bolts 7, and by the application of nuts to the bolts, as shown in Fig. 1, the two sections of the 45 box are held securely and rigidly in place. The box encircles the rod 8 and carries therein an annular swab 15, which is preferably formed of felt and arranged with its inner edge in contact with the rod, so as to wipe or 50 swab the same as the rod reciprocates. The swab 15 is held properly in engagement with the rod by a spring 16, one end of which is fastened to a pin 17, fitted in a hollow protuberance 18 on the section 10 of the swab-box. 55 The spring 16 passes around the outer edge of the swab and back to and beyond the pin 17, and by properly tensioning the spring it is made to press the swab against the rod. The hollow protuberance 18 serves, further, 60 as an oil-cup, into which oil may be poured to keep the swab 15 saturated, and this serves, therefore, not only to clear the rod of matter attached thereto, but, further, to supply it with lubricant as it enters the stuffing-box. 65

Having thus described my invention, I claim as new and desire to secure by Letters Patent—

A rod-swab, comprising a circular case or box formed of two sections hinged together 70 and adapted to contain a swab, each section being provided with an apertured lug, and one of the sections with a hollow protuberance, and a circular spring having one end secured in the protuberance and its free end 75 extending under its fixed end; substantially as described.

In testimony whereof I have signed my name to this specification in the presence of two subscribing witnesses.

JOSEPH ONESIME DAUPHIN.
